UNITED STATES PATENT OFFICE.

PERCY R. DRENNING, OF BALTIMORE, MARYLAND, ASSIGNEE, BY MESNE ASSIGNMENTS, TO T. H. SYMINGTON AND SON, INC., OF BALTIMORE, MARYLAND, A CORPORATION OF MARYLAND.

DOOR-SECURING DEVICE.

Application filed November 7, 1925. Serial No. 67,553.

This invention relates to door securing devices.

The principal object of the invention, generally stated, is to provide a securing device particularly adapted for use in connection with the doors of refrigerator cars for the purpose of forcing the doors into closed position and effectually maintaining them fully closed so as to prevent leakage of air and change of temperature within the car, and to provide for the initial opening of the doors.

An important object of the invention is to provide securing means having lever mechanism for moving the same to operative or inoperative position, as the case may be, the lever mechanism having associated therewith retaining means capable of having the conventional seal applied thereto.

A more specific object of the invention is the provision of door securing means embodying pivoted bar elements carried by a door and coacting with peculiarly constructed keepers mounted on the door frame, the keepers having cam portions acting initially to force the doors partly shut and having other portions which act to bend the bar elements slightly for holding them securely in position and applying pressure to the doors, urging them closely to their seats so that absolute closure will be assured.

Still another object of the invention is to provide securing means which embodies a small number of parts and which will, therefore, be simple and inexpensive to manufacture and install, easy to operate, positive in action, efficient and durable in service, and a general improvement in the art.

To the attainment of the foregoing and other objects and advantages, the invention preferably consists in the details of construction and the arrangement and combination of parts to be hereinafter more fully described and claimed, and illustrated in the accompanying drawings in which:

Figure 1 is an elevation of the invention applied to a refrigerator car door, the locked position being illustrated by full lines and the released or inoperative position being shown by dotted lines;

Figure 2 is a vertical section taken substantially at the meeting edges of the doors;

Figure 3 is a horizontal section through the door frame in a plane above the upper

retaining member, the door being shown in the partly open position, and

55

Figure 4 is a detail perspective view of one of the retaining members carried by the door frame.

Referring more particularly to the drawings, the numeral 1 designates a portion of a refrigerator car having an opening 2 adapted to be closed by a pair of doors 3 mounted as for instance by means of hinges 4 and having inclined coacting meeting edges 5 as well as inclined upper and lower edges 6. The construction of the door and its frame is well known and it is of course apparent that it is highly desirable to apply pressure to the outside of the door or doors for the purpose of forcing the same tightly into place so as to prevent passage of air which might change the temperature within the car.

In carrying out the invention I provide securing means comprising a lever 7 pivotally mounted midway between its reaction ends, 75 as shown at 8 within a suitable bracket structure 9, and I also utilize bolts 10 pivoted as at 11 within brackets 12 and pivotally and slidably connected with the lever 7 as by means of pivot elements 13 passing through the end portions of the lever 7 and through elongated slots 14 in the bolts 10. During movement of the bolts 10 into operative or inoperative position, pivoting action occurs at the points 8, 11 and 13 as indicated by the dotted lines 85 and dot and dash lines in Figure 1. Suitable guide brackets 15 may be provided for applying pressure from bolt 10 to the door and limiting the movement of the bolts 10, these brackets being located at any desired points, 90 though preferably near the upper and lower edges of the door. All of these parts are mounted on one of the doors 3. The bolts 10 are of such length as to project beyond the top and bottom of the door structure and 95 their upper and lower extremities are formed with preferably cylindrical extensions 16 for a purpose to be described. The bolts 10 themselves may be rectangular in cross section.

Mounted on the door frame or at the outside of the car above and below the door opening 2 are retaining devices indicated generally by the numeral 17. These devices are of similar construction and each may be formed as a single bracket bolted or otherwise suitably secured to the car or door frame. Each

bracket includes a main or body portion 18 formed with a slot 19 which is slightly inclined with respect to the outer surface of the door, these slots in the brackets being adapted to receive the end portions of the bolts 10 for holding the doors in closed position. Each bracket further includes a guide portion 20 of a housing-like construction communicating with the slot 19 and having a curved passage 21 therein defined between curved wall portions 22 and 23, the wall portions 22 and 23 acting as a cam. The curved passages 21 are adapted to receive the extensions 16 on the bolts 10 during the initial forcing of the doors 15 to closed position. The portions 20 of the retainers or keepers extend only a part way of the entire length thereof, the intention being that the extensions 16 may pass entirely through and beyond the portions 20 by the 20 time the bolts 10 enter the slots 19.

The lever 7 is formed at one end with a preferably laterally inclined extension 24 constituting a handle adapted to be grasped and swung in one direction or the other to effect movement of the bolts 10 to released or holding position, as the case may be. In the present instance the handle 24 is shown as slotted at 25 so as to be engaged upon a staple or the like 26 through which may be passed a padlock, seal or the like when the securing device is in its holding position, the engagement of the handle upon the staple acting to prevent accidental movement of any of the parts into released position.

35. In the operation, assuming that the doors are open, to effect closing and fastening thereof, it is first necessary that the doors be pushed, in any suitable manner, into substantially closed position. At such a time the 40 handle 24 is in the position shown by dotted lines in Figure 1 and the lever 7 and bolts 10 are in the positions illustrated by dot and dash lines in the same figure, the bolts 10 being at one limit of their movement. The operator then grasps the handle 24 and forces it downwardly or toward the position shown by full lines in Figure 1. As this is done the cylindrical extensions 16 on the bolts enter the guide portions 20 of the retaining members or brackets 17 and as the extensions 16 ride along the curved cam surfaces 23, it is evident that these cam surfaces will act to move the bolts 10 toward the doors, thus moving them toward their seat. As the movement of the handle 24 is continued, the extensions 16 ride out from the guide members 20 by the time the ends of the bolts enter the 55 slots 19. The slight inclination of the slots 19 is sufficient to effect a final wedging action 60 which will result in positively forcing the door or doors into fully closed position.

Assuming that the doors are closed and that it is desired to open the same, the handle 24 is disengaged from the staple 26 and moved 65 from the full line position to the dotted line

position shown in Figure 1, the end portions of the bolts riding out of the slots 19, subsequently to which the extensions 16 ride along the passages 21 in the guide members 20, the engagement of these extensions with the curved walls 22 of the bracket members 17 resulting in producing a camming action which will start the opening movement of the doors, this feature being of distinct importance in case the doors should stick from swelling or any other reason. By the time the bolts reach the ends of the guide brackets or members 15 the extensions 16 will be clear of the bracket portions or members 20 so that the doors may then be opened to the full extent without hindrance.

From the foregoing description and a study of the drawings it will be evident that I have provided a highly efficient door securing means which is, moreover, easy to operate and which embodies means for not only forcing the doors closed but also for forcing them open when occasion arises. The slight bending action applied to the securing bolts operates to maintain the parts against casual movement in addition to imparting considerable pressure to the doors for positively insuring full closure thereof under all natural circumstances.

While I have shown and described the invention as applied to the doors of refrigerator cars, it should be understood that this is merely an exemplification inasmuch as the structure may be employed just as satisfactorily in connection with doors of ordinary refrigerators, ice boxes, cold storage vaults and in fact in other places which may suggest themselves. It is likewise to be understood that I reserve the right to make all such changes in the form, arrangement and combination of parts as will not depart from the spirit of the invention or the scope of the claims hereunto appended.

Having thus described the invention, I claim:

1. In combination with a door and an opening within which the door seats, a lever pivoted on the door, bolts pivoted on the door and pivotally and slidably connected with the lever, guide means on the door for applying pressure to and for limiting movement of the bolts, and keeper means adjacent the door opening having curved cam passages therein extending a portion of the length thereof and further having slots inclined with respect to the face of the door for receiving the bolts and wedging and bending the same.

2. Means for forcing a door into closed position within an opening, comprising bolts pivotally mounted on the door for swinging movement in a plane parallel therewith, means for swinging the bolts, means on the door for limiting movement of the bolts in both directions, and keeper means stationarily mounted adjacent the door opening for

receiving the bolts, said keeper means having cam portions for initially moving the door into closed or open position, the keeper means further having bolt receiving portions angularly arranged and acting to apply bending strain to the bolts.

3. A device for forcing a door into closing relation to a door opening comprising pivotally mounted bolts on the door, means for moving the bolts, and keeper means mounted adjacent the door opening, each keeper means including a guide portion having opposed curved walls defining a cam passage receiving the extremity of a bolt, and further having an inclined slot at the inner end of the passage for receiving a bolt, the guide portion terminating short of said slot.

4. In a door closing, securing and opening mechanism, a door adapted to fit within an opening for closing the same, bolts pivotally mounted on the door and swingable in a plane parallel therewith, guide means for the bolts, and keeper brackets mounted adjacent the door opening, each bracket having a guide portion formed with a curved passage initially receiving the extremity of a bolt for forcing the door closed, each bracket further including an inclined slotted portion communicating with the passage for receiving a bolt and engaging the same at a point spaced from the extremity.

5. In a door closing, securing and opening mechanism, a door adapted to fit within an opening for closing the same, bolts pivotally mounted on the door and swingable in a plane parallel therewith, guide means for the bolts, and keeper brackets mounted adjacent the door opening, each bracket having a guide portion formed with a curved passage initially receiving the extremity of a bolt for forcing the door closed, each bracket further including a slotted portion for receiving a bolt and engaging the same at a point spaced from the extremity, the extremity of each bolt being reduced and rounded to facilitate its movement along the curved passage and to avoid torsion strains.

6. In a door closing, securing and opening mechanism, a door adapted to fit within an opening for closing the same, bolts pivotally mounted on the door and swingable in a plane parallel therewith, guide means for the bolts, and keeper brackets mounted adjacent the door opening, each bracket having a guide portion formed with a curved passage initially receiving the extremity of a bolt for

forcing the door closed, each bracket further including a slotted portion for receiving a bolt and engaging the same at a point spaced from the extremity, the extremity of each bolt being reduced and rounded to facilitate its movement along the curved passage and to avoid torsion strains, said guide portion extending from one end of the bracket to the slotted portion whereby the bolt will be guided into the slotted portion.

7. In a door closing, securing and opening mechanism, a door adapted to fit within an opening for closing the same, bolts pivotally mounted on the door and swingable in a plane parallel therewith, guide means for the bolts, keeper brackets mounted adjacent the door opening, each bracket having a guide portion formed with a curved passage initially received the extremity of a bolt for forcing the door closed, each bracket further including a slotted portion for receiving a bolt and engaging the same at a point spaced from the extremity, the extremity of each bolt being reduced and rounded to facilitate its movement along the curved passage and to avoid torsion strains, said guide portion extending from one end of the bracket to the slotted portion whereby the bolt will be guided into the slotted portion, and lever means connected with the bolts for swinging the same simultaneously.

8. In a door closing, securing and opening mechanism, a door adapted to fit within an opening for closing the same, bolts pivotally mounted on the door and swingable in a plane parallel therewith, guide means for the bolts, keeper brackets mounted adjacent the door opening, each bracket having a guide portion formed with a curved passage initially receiving the extremity of a bolt for forcing the door closed, each bracket further including a slotted portion for receiving a bolt and engaging the same at a point spaced from the extremity, the extremity of each bolt being reduced and rounded to facilitate its movement along the curved passage and to avoid torsion strain, said guide portion extending from one end of the bracket to the slotted portion whereby the bolt will be guided into the slotted portion, lever means connected with the bolts for swinging the same simultaneously, and means engageable by the lever for holding the same rigid.

In testimony whereof I affix my signature.

PERCY R. DRENNING.
